UNITED STATES PATENT OFFICE

146,133

DESIGN FOR AN ADJUSTABLE VENTILATOR FOR AIRPLANES

Carl F. Gladen, Bay City, Mich.

Application October 27, 1944, Serial No. 116,002

Term of patent 7 years

(Cl. D71—1)

To all whom it may concern:

Be it known that I, Carl F. Gladen, a citizen of the United States and a resident of Bay City, in the county of Bay and State of Michigan, have invented a certain new, original, and ornamental Design for an Adjustable Ventilator for Airplanes, of which the following is a specification, reference being had to the accompanying drawing, forming a part thereof.

In the drawing:

Fig. 1 is a front face elevational view of an ad-

justable ventilator for airplanes, showing my new design.

Fig. 2 is an edge elevational view thereof.

Fig. 3 is a view similar to Fig. 1 showing the opposite side of the ventilator.

Fig. 4 is a transverse-sectional view taken on the line 4—4 of Fig. 1.

What I claim is:

The ornamental design for an adjustable ventilator for airplanes, as shown.

CARL F. GLADEN.
